UNITED STATES PATENT OFFICE.

JOHN F. HUGHES, OF LANSDOWNE, PENNSYLVANIA.

DUMPING-WAGON.

1,122,394.

Specification of Letters Patent. Patented Dec. 29, 1914.

Application filed March 23, 1911. Serial No. 616,303.

To all whom it may concern:

Be it known that I, JOHN F. HUGHES, a citizen of the United States, and a resident of Lansdowne, in the county of Delaware and State of Pennsylvania, have invented certain new and useful Improvements in Dumping-Wagons, whereof the following is a specification, reference being had to the accompanying drawings.

- 10 My invention particularly relates to dumping wagons of the class usually employed in conveying loose material, such as sand, coal, bricks, etc., which may be discharged in bulk, and in which the body is so supported upon the supporting structure as to have an oscillatory movement whereby it may be tilted to discharge its contents or load. In previous constructions of this character, in so far as I am aware, it has been necessary to apply some force other than gravity to cause the receptacle or body of a wagon or similar vehicle to tilt to discharge its load and to cause the readjustment of the same to its normal position.
- 25 One of the objects of my invention is to provide a wagon having an oscillatory receptacle or body which will automatically tilt to discharge its contents or load when the driver withdraws the latch or trigger or other means which may be used for holding the body in its normal position and which receptacle or body will readjust itself automatically to normal position after its load has been discharged. Other dumping wagons of this character which have been heretofore constructed require, as already indicated, some force other than and in addition to gravity to cause the receptacle or body to completely and automatically perform the acts of tilting to discharge its contents or load and readjustment to normal position. The operation of discharging the contents or load from the receptacle or body has generally been performed heretofore in three distinct acts,—first, by tilting the body, usually by hand, to a dumping position; second, the dumping of the load, which is the act of gravity; and third, the readjustment of the receptacle or body which may be performed in various ways. By the employment of my invention these acts of tilting the receptacle or body, discharging the contents or load therefrom, and the readjustment of the receptacle or body to its normal position, are performed by the action of

gravity and require no other force to effect a complete operation. The peculiar and novel construction and arrangement of the parts of the structure embodying my invention, make this possible. In a structure embodying my invention the axis of oscillation of the receptacle or body is so situated that the center of gravity thereof is in front of the axis of oscillation from normal position when the said receptacle or body is empty, 60 while the center of gravity of the combined weights of the receptacle or body and its contents or load is situated in rear of such axis of oscillation.

In the structure embodying my invention 70 I have also provided means for utilizing the tail board of the body or receptacle as a counter-weight, whereby a sufficient amount of energy may be accumulated to readjust the receptacle or body to its normal position 75 after the load is dumped or discharged.

At the time that the receptacle or body tilts to discharge its load the tail-board which acts as a counter-weight is raised. This counter-weight assists in causing the 80 body to readjust itself to normal position. The tail-board in acting as a counter-weight or potential energy accumulator thereby becomes the means by which the kinetic energy 85 exerted in dumping the load may be used in effecting readjustment of the body.

Further objects of my invention are to provide a construction in which the axis of oscillation of the receptacle or body from its normal position lies in a plane forward 90 of the axle of the rear wheel of the wagon so that the weight of the receptacle either empty or loaded is disposed on the wagon between the front and rear axles and so that sufficient weight is thrown upon the 95 front wheels of said wagon to prevent lateral skidding; to provide the receptacle with an auxiliary axis of oscillation rearward of the rear axle of the wagon, upon which axis the receptacle may rock after oscillating on 100 the main axis sufficiently to shift the center of gravity of the load back of the plane of said auxiliary axis; and to provide means to maintain the receptacle in a fixed oscillatory path with respect to the wagon frame; to 105 provide means to retain the receptacle in its normal or operative position, to provide means to release said receptacle; and to provide a tail gate arranged to be automatically shifted out of normal position by the dump- 110

ing action of said receptacle, and tending when in abnormal position to return said receptacle to its normal position.

This invention further includes all of the 5 various novel features of construction and arrangement hereinafter more definitely specified.

In the accompanying drawings Figure 1 is a vertical, longitudinal sectional view of a 10 dumping wagon conveniently embodying this invention, certain portions thereof being shown in side elevation for convenience of illustration; Fig. 2 is a fragmentary, sectional view of the wagon shown in Fig. 1, 15 showing the receptacle in dumped position; Fig. 3 is a fragmentary side elevational view of the supporting bar carried by the frame, upon which the receptacle rests, and the relative positions of the supporting chair 20 carried by the receptacle; Fig. 4 is a fragmentary plan sectional view of one of the 25 guides and its respective guide-way; and Fig. 5 is a diagrammatic plan view on a reduced scale of the receptacle *per se*.

In said figures the frame of the wagon 25 is supported upon the front and rear axles 7 and 8, respectively carried by the wheels 9 and 10 and comprises the side rails 12, 30 preferably formed of angle irons, which are looped upwardly at 14 to provide a mounting for the seat bolster 15 carrying the springs 16, upon which the seat 17 is mounted. Said side rails 12 are conveniently braced intermediate of their ends by the 35 cross beam 19 and their horizontal webs, each carry a bar 20, which extends rearwardly over and slightly beyond the rear axle 8 of the wagon and is slightly deflected downward as shown at 21. Attached to the 40 vertical flange of each of the respective side bars 12 are the rearwardly extending bars 22, which extend obliquely upward from the rear axle 8 and terminate in a vertical extension 23 in close proximity to the rear 45 end of the receptacle 25. The receptacle 25 is mounted for oscillation upon said frame and is provided with a supporting member or chair 26, which has a relatively short bearing surface 27, and which extends 50 obliquely upward from the opposite ends of said short bearing surface, and is provided with extensions 28 and 29 respectively secured to the under side of the floor 30 of the receptacle 25, and to cleats 31, 32 55 and 33 on the under side of the floor.

As best shown in Fig. 5, the receptacle 25 is formed wedge-shaped, having its minimum width at its forward end, and its maximum width at its rearward end, whereby 60 its center of gravity when empty is farther toward the forward end than when loaded, so that when its center of oscillation is disposed between the center of gravity, when empty and the center of gravity when loaded, it will tend to automatically return to

its normal position when empty and when loaded will tend to discharge the load, upon being released.

The supporting member or chair 26 provides an edge or corner 38, which rocks upon the bar 20 as best shown in dot and dash line in Figs. 2 and 3 until the extension 28 of said supporting member engages the end 21 of said bar 20 upon which it rocks as a center, entirely raising the chair 26 from 70 said bar 20 and providing an auxiliary axis of oscillation which is farther back than the axis of oscillation 38 and upon which the receptacle 25 with its load continues to oscillate until it reaches the position 75 shown in Fig. 2, at such an angle as to permit the load to slide therefrom.

In order to maintain the receptacle 25 in a fixed path relative to the frame of the wagon, said receptacle is provided with 80 guide bars 40 respectively secured to the opposite sides of the receptacle, by bolts 41. Each guide 40 is provided with a downwardly and rearwardly curved projection 42, which extends through the guide way 43 85 formed by the strap 44, which is secured to the bar 22 by bolts 45.

The oscillatory movement of the receptacle 25 upon its axis of oscillation at 21 is limited by a pin 48 carried by the curved 90 projection 42 of each of the guide bars 40, which pin, as best shown in Fig. 2 engages the under side of the axis strap 49 of the 95 wagon frame.

The tail gate 50, which forms the rear 100 wall of the receptacle 25, is provided with forwardly and upwardly extending arms 51 which extend straight for a distance from said tail gate and then curve upwardly, and are pivoted at 53 to the upper end of the 105 respective guide bars 40.

The arm 51 of the tail gate 50 is arranged to ride upon the roller 54, which is mounted for rotation upon the shaft 55 in the upper extremity 23 of the bar 22, said arm 51 being of such shape as to effect the uplifting of the tail gate 50 when the receptacle is shifted to the dumped position shown in Fig. 2, so that when the load is discharged from said receptacle, the tail gate serves to 110 start the rocking of the receptacle upon its rearward axis of oscillation back to its normal operative position, until fitted to form 115 the end closure of the receptacle 25 as shown in Fig. 1.

The receptacle 25 is retained in its normal operative position as shown in Fig. 1 by a 120 detent lever 60, which is pivoted intermediate of its ends upon the pintle 61 to the lugs 62 of a plate 63 secured to the under side of 125 the seat bar 15, and between the upper ends of a pair of plates 64, which in turn are secured to the under side of the cross beam 19 and project forwardly and upwardly therefrom to a point in front of the receptacle 25 130

and intermediate the altitudinal limits thereof. The lower end of the detent lever 60 is arranged to engage a detent bracket 65 secured to the front wall 66 of the receptacle 25 and is arranged to normally retain the receptacle 25 in its operative position shown in Fig. 1. Said detent lever 60 is connected by the chain 68 to the foot lever 69, which is pivoted at 70 and arranged to be shifted 10 in the direction indicated by the arrow thereon in Fig. 1 to disengage said detent lever 60 from the detent bracket 65, in opposition to the tension of the spring 72, which normally tends to shift said lever 60 15 to its operative position to engage the detent bracket 65.

The foot lever 69 is arranged to oscillate in the guide 75, which is provided with an aperture 76 into which a pin 77 may be 20 fitted to prevent the accidental movement of the foot lever to effect the premature dumping of the load carried by the receptacle 25; this pin, however, is not an essential element but is merely a preventative to insure 25 against carelessness.

A wagon constructed in accordance with the invention is advantageous in that the operator may actuate the dumping mechanism without dismounting from the seat 17 30 or without releasing control of the team, and by merely proceeding from the discharged contents of the receptacle 25, may effect the automatic return of said receptacle to its normal operative position.

It is not desired to limit this invention to the precise details of construction and arrangement herein set forth, as it is obvious that various modifications may be made 35 therein without departing from the essential 40 features of the invention as defined in the appended claims.

Having thus described my invention, I claim:

1. In a dumping wagon comprising a 45 frame, the combination with an oscillatory

receptacle arranged to carry its greatest load rearward of the plane of its center of gravity, of a supporting member having a relatively short bearing surface slightly rearward of the center of gravity of said receptacle when empty, and arranged to rest upon said frame forward of the rear axle of said wagon, said receptacle being arranged to first rock on the corner of said support, and to then rock upon the rear corner of said frame, rearward of said axle, curved guides carried by said receptacle, and guide-ways carried by said frame co-operative with said guides to maintain said receptacle in oscillatory relation with said frame. 50 55 60

2. In a dumping wagon comprising a frame, the combination with an oscillatory receptacle arranged to carry the greatest load rearward of the plane of the center of gravity, of a supporting member having a 65 relatively short bearing surface slightly rearward of the center of gravity of said receptacle when empty and arranged to rest upon said frame forward of the rear axle of said wagon, said receptacle being arranged 70 to first rock on the corner of said support and then to rock on the rear corner of said frame rearward of said axle, curved guides carried by said receptacle, guide-ways carried by said frame co-operative with said 75 guides to maintain said receptacle in oscillatory relation with said frame, arms extending upwardly and rearwardly from the opposite sides of said frame, pivoted arms having pivotal connection with the said 80 guides and being provided with a tail-board upon their outer ends and being supported intermediate their ends upon the arms extending upwardly from said frame.

In witness whereof, I have hereunto set 85 my hand this 17th day of March, A. D. 1911.

JOHN F. HUGHES.
